UNITED STATES PATENT OFFICE.

JOSÉ KECKEIS, OF PORTLAND, OREGON.

EDUCATIONAL APPLIANCE FOR ARITHMETIC.

1,378,241.

Specification of Letters Patent. Patented May 17, 1921.

Application filed April 14, 1920. Serial No. 373,697.

To all whom it may concern:

Be it known that I, José Keckeis, citizen of the United States, residing at Portland, in the county of Multnomah and State of 5 Oregon, have invented a new and useful Educational Appliance for Arithmetic, of which the following is a specification.

My invention relates to improvements in educational appliances for arithmetic, in 10 which a marble falls through openings in a concave dish and finally comes to rest on some numeral, the factors of which are visible, while the product as represented by said numerals remains invisible until the 15 marble is removed.

The objects of my invention are to furnish an inexpensive device which, under the guise of a fascinating game, develops the mathematical faculties of children.

20 Other objects and advantages are to be found in the general arrangement and the details of construction, as will be explained hereafter.

I attain these objects with the mechanism 25 illustrated in the accompanying drawing, in which—

Figure I is a plan view of the entire apparatus, part of the top being removed to show the construction underneath.

30 Fig. II is an elevation of Fig. I, the left half thereof being shown in section.

Similar numerals refer to similar parts throughout the several views.

Since multiplication is the subject which 35 presents the most difficulty to the child, the details of construction shown in the drawing refer particularly to this branch of study, but the same device with very slight alterations can equally well be used to teach 40 addition, subtraction and division, as will be described below.

A circular base of wood *a* has the upper surface sloping from the center toward the periphery. Projecting upwardly at the periphery is the rim *b*. Radiating from the post *c* at the center of the base, and resting on said base, are the walls *d* which divide the space around the post into eight compartments corresponding with the multipliers from 2 to 9 in a multiplication table. The multiplier 1 does not require extensive memorizing and is therefore omitted. A cylindrical wall *e* closes said compartments at the periphery. It should, however, be 55 noted that this wall *e* does not extend down

to the base, but leaves clearance enough so that a marble can pass through unhindered. The multiplicands from 2 to 9 for each compartment are printed on the lower outside edge of the cylindrical wall, while the multiplier is printed above the multiplicands. Finally the compartments are covered by a concave dish *f* whose openings *g* permit a marble to fall into the respective compartment underneath. The upwardly extending 60 rim *h* at the periphery of the concave dish prevents a marble from leaving the dish, and the concave hub *i* at the center of the dish may be utilized as a storage place for such marbles as are not needed in the game. 70

The play is conducted as follows: One or more children take their places at the apparatus. A marble is thrown tangentially into the dish, where it will circulate till it drops through one of the openings into the compartment, say 7, below. Rolling down the inclined surface of the base board, said marble will perhaps emerge at a point where the multiplicand 2 is printed at the edge of the cylindrical wall. Once emerged at this 75 point, the marble passes between the pins *j* into a groove *k*, at the end of which the numeral 14, as the product of 7 times 2, is printed or stamped. The factors being 80 plainly visible all the time, the child is 85 called upon to announce the product before it is permitted to remove the marble and to verify its computation with the numeral underneath. A prize may reward the best performer. 90

Addition can be practised in the same way except that thin strips of metal with the correct sums stated thereon should be used to cover the numerals which present products in the multiplication table. It is a 95 simple matter to corrugate the strips in conformity with the grooves in the edge of the base.

In subtraction and division the multiplier is covered by some other suitable numeral, 100 and the numerals of the previously described metal strip must then conform to the respective operation.

Having thus explained by invention it will be seen that my objects have been accomplished, and, though I have shown the preferred form of construction, I reserve to myself the right to make minor changes providing I do not violate the spirit and principle of my invention. Especially do I 110

wish to emphasize that wood is really the ideal material for children's use, but that I do not wish to bar myself from the use of sheet metal or card board or a combination of all of these, if necessary.

I claim:

1. An educational appliance, comprising a circular base having a convex surface, a plurality of numbered grooves radiating 10 toward the circumference, a post in the center of the base, a concave dish supported on the post, a plurality of apertures in the dish around the post, and a plurality of numerals segregated into series on the periphery of 15 the concave dish, the individual numbers in the series indicating an individual groove in said base and bearing a definite arithmetical relation to the number in the groove.
2. An educational appliance, comprising 20 a circular base having a sloping upper surface and an upwardly extending rim at the circumference, sectoral compartments radiating from the center toward the edge, a space between the lower edge of the peripheral wall of said compartments and the base 25 to permit the passage of a marble, a concave dish covering the top of said compartments

and openings in the bottom of said concave dish to permit a marble circulating in said dish to enter non-selectively one of the compartments below said dish.

3. An educational appliance, comprising a circular base having a sloping upper surface, corrugations in the upper surface near the edge, an upwardly extending rim around the circumference of said base, compartment walls radiating from the post toward the edge, a peripheral wall connecting the upper portions of said compartment walls, a plurality of pins in spaced relation dividing the open portion between base and peripheral wall into equal parts, a concave dish resting on the post and compartment walls having an upwardly extending rim at the circumference and having openings in 45 the bottom of said dish communicating with the compartments underneath, whereby a marble may enter one compartment and proceed through the pins to the rim at the base.

Signed by me at Portland, Oregon, this 8th day of April, 1920.

JOSE KECKEIS.
